[57] CLAIM

The ornamental design for a safety propane tank carrier, as shown and described.

DESCRIPTION

FIG. 1 shows a perspective view of my claimed design;

FIG. 2 shows an enlarged perspective view of a strap

connection point of my claimed design;

FIG. 3 shows a top view of my claimed design on a reduced

scale;

FIG. 4 shows a bottom view of my claimed design on a reduced

scale;

FIG. 5 shows a side view of my claimed design on a reduced

scale; and,

FIG. 6 shows the opposite side view of my claimed design on a reduced scale.

The broken line showing of a propane tank is for illustrative purposes only and forms no part of the claimed design.
